(57) **CLAIM**

The ornamental design for a tri-bladed drone propeller, as shown and described.

DESCRIPTION

FIG. 1 is a perspective view of a tri-bladed drone propeller showing my new design;
 FIG. 2 is a front view thereof;
 FIG. 3 is a back view thereof;
 FIG. 4 is a left-side view thereof;
 FIG. 5 is a right-side view thereof;
 FIG. 6 is a top view thereof; and,
 FIG. 7 is a bottom view thereof.

1 Claim, 5 Drawing Sheets**FIG. 1**

FIG. 2

FIG. 3

FIG. 4

FIG. 5

FIG. 6

FIG. 7
